UNITED STATES PATENT OFFICE

129,472

DESIGN FOR A GAME BOARD

Ida Pauline Cassidy, Warrensburg, N. Y.

Application June 11, 1941, Serial No. 101,405

Term of patent 14 years

To all whom it may concern:

Be it known that I, Ida Pauline Cassidy, a citizen of the United States, residing at Warrensburg, in the county of Warren and State of New York, have invented a new, original, and ornamental Design for a Game Board, of which the following is a specification, reference being had to the accompanying drawing, forming part thereof.

The single figure is a top plan view of a game board showing my new design.

The game board is of no appreciable or substantial thickness.

I claim:

The ornamental design for a game board, as shown and described.

IDA PAULINE CASSIDY.
